[57] CLAIM

The ornamental design for a dual compartment container for measuring and storing fluids, as shown and described.

DESCRIPTION

FIG. 1 is a perspective view of a dual compartment container for measuring and storing fluids;

FIG. 2 is a side view thereof;

FIG. 3 is a right end view thereof;

FIG. 4 is a left end view thereof;

FIG. 5 is a top view thereof; and

FIG. 6 is a bottom view thereof.
